UNITED STATES PATENT OFFICE.

BEVERLY L. WATERS, OF AURORA, ILLINOIS.

SHELVING.

No. 910,616.

Specification of Letters Patent.

Patented Jan. 26, 1909.

Application filed April 27, 1908. Serial No. 429,379.

To all whom it may concern:

Be it known that I, BEVERLY L. WATERS, a citizen of the United States, residing at Aurora, in the county of Kane and State of Illinois, have invented a certain new and useful Improvement in Shelving, of which the following is a specification.

My invention relates to metallic sectional shelving wherein the shelves extend from one partition to another and the sections are of a length equal to the length of a shelf.

The present invention is closely related to the one shown and described in my copending application filed April 27, 1908, Serial No. 429,490. In that application the rods which support the shelves are formed to interfit directly one with another, the interfitting portions being screw threaded so that the rods may be screwed together by merely screwing one into the other without the use of an intermediate coupling element. In such construction however, one end of the rod must be of reduced diameter and this requires either machine work to cut away a portion of the stock if a solid rod is used or forge work if a hollow tube like rod is employed.

The present invention contemplates a structure in which both ends of the rod are threaded, the coupling being made through the agency of a threaded stud.

Referring to the accompanying drawings, wherein like parts are denoted by like reference numerals, Figure 1 is a perspective view of shelving embodying my invention. Fig. 2 is a fragmentary sectional elevation taken through the shelf from front to rear. Fig. 3 is a bottom sectional view taken on the line 3—3 Fig. 2. Fig. 4 is a sectional view taken on the line 4—4 Fig. 3. Fig. 5 is a sectional view showing a cap screw holding the tie rod at the end of the shelving.

Fig. 6 is a perspective view of the preferred form of stud. Fig. 7 is a longitudinal sectional view of the tie rod made from a solid piece of metal instead of from a hollow tube.

The structure comprises four principal kinds of elements, to wit, the vertical partitions 10, the shelves 11, the tie rods 12 and the coupling studs 13. The partitions are preferably stiffened by means of marginal strips 14 which are enlarged cylindrically and are otherwise especially constructed in the manner described and claimed in an application filed by me April 17, 1908, Serial No. 427,693. The shelves 11 may be stiff-

ened by longitudinal flanges 15 although these form no part of the present invention. It is desirable also that these shelves be further stiffened by means of flanges 16 as shown in the copending application last referred to.

The tie rods 12 are alike at each end and are slightly shorter than the shelves, so that when the rods are tightened the shelves will come to a bearing against the sides of the partitions for the purpose of holding the shelves in place and bracing the structure. When a tubular tie rod is employed as shown in Figs. 2 to 5 it is desirable that the ends be thickened somewhat by forging or swaging. This affords sufficient material to receive the tap without unduly weakening the part. When the parts are assembled, the studs 13 extend through the partition 10 which is apertured to receive it as shown in Fig. 4, one end of the stud lying within the end of the rod on one side of the partition and the other end of the stud lying within the corresponding rod on the opposite side of the partition. The stud has a collar 17 formed thereon preferably integral therewith and in most instances it is desirable to form a number of flat surfaces 18 on said collar for receiving a wrench whereby the stud may be screwed into the end of the rod. The custom in shipping shelves of this construction is to tightly screw a stud in one end of each of the tie rods until the collar 17 abuts the end of the rod as shown at the left part of Fig. 4. This makes the rod and stud constitute what is practically a single element of the structure, which obviously facilitates assembling at the place where the shelving is to be erected. The collar 17 has another function, to wit, that of affording a bearing surface or shoulder for contacting the side of the partition.

It is clear that when the parts are assembled in the manner shown and described, and the rods are screwed up tight, the structure will exhibit great rigidity combined with simplicity of construction. The tie rods will be free of protuberances with the result that the shelves may lie flat thereon throughout the entire length of the rod. The rods will be interchangeable end for end, at least until after the stud has been screwed home into one end as above indicated, thus requiring only one kind of threading tool for the rods.

The screw threads upon the coupling all run in the same direction with the result that

the tightening of one rod upon the coupling tends to tighten the coupling into the companion rod.

Although the tubular form of tie rod is 5 preferable on account of its smaller weight, a solid rod 19 such as is indicated in Fig. 7 may be substituted without altering the co-operative relationship of the parts.

The shelving is finished off at the ends by 10 screwing cap screws 20 into the ends of the rods to hold the partitions in place in the manner indicated in Fig. 5.

What I claim as new, and desire to secure by Letters Patent, is:

15 1. In shelving, the combination of an upright partition, a shelf extending therefrom on each side thereof, a tie rod beneath each shelf internally threaded at the end, an externally threaded coupling member penetrating 20 said partition and adapted to screw into the end of said rods for holding the structure together, and a collar upon said coupling member intermediate of the ends thereof, whereby the stud may be tightened 25 into the end of one of the tie rods previous to the erection of the structure.

2. In shelving, the combination of an upright partition, a shelf extending therefrom on each side thereof, a tie rod beneath each

shelf internally threaded at the end, and an externally threaded coupling member penetrating 30 said partition and being screw threaded whereby it is adapted to screw into the ends of said rods for holding the structure together, all the threads upon said coupling 35 member running the same way so that the tightening of one rod relatively to the coupling member will also tend to tighten the coupling member relatively to the other rod.

3. In sectional shelving, the combination 40 of upright partitions, horizontal shelves, tie rods beneath said shelves, said tie rods being internally threaded at their ends, and double ended screw studs penetrating the partition and adapted to screw into the proximate 45 ends of the tie rods on opposite sides of the partition, said shelves being longer than the rods whereby the shelves will be the first to come to a bearing against the partitions and will consequently be held firmly in position 50 when the rods are tightened.

In witness whereof, I have hereunto subscribed my name in the presence of two witnesses.

BEVERLY L. WATERS.
